UNITED STATES PATENT OFFICE.

CHARLES H. COWDREY, OF FITCHBURG, MASSACHUSETTS.

WOOD-TURNING LATHE.

SPECIFICATION forming part of Letters Patent No. 273,227, dated February 27, 1883.

Application filed May 8, 1882. (No model.)

To all whom it may concern:

Be it known that I, CHARLES H. COWDREY, of Fitchburg, in the county of Worcester and State of Massachusetts, have invented certain Improvements in Wood-Turning Lathes, of which the following is a specification.

This invention relates, first, to the holder of the roughing-tool; secondly, to the holder of the forming tool or tools; and, thirdly, to the cutting-off tool, all of which are supported on the center-carriage of a lathe.

The invention has for its object to provide improved means for adjusting the roughing-tool and for adjusting and operating the tool-holder and cutting-off tool.

To these ends my invention consists in the improved mechanism which I will now proceed to describe and claim.

Of the accompanying drawings, forming part of this specification, Figure 1 represents a side elevation of a portion of a lathe embodying my improvements. Figs. 2 and 3 represent respectively sections on lines $x\ x$ and $y\ y$, Fig. 1, looking toward the carriage. Fig. 3^a represents a plan view of the center-rest and the rougher bed and tool. Fig. 4 represents a perspective view of the cutting-off tool and the devices for operating the same. Figs. 5 and 6 represent respectively sections on lines $z\ z$ and $z'\ z'$, Figs. 2 and 1. Fig. 7 represents a transverse section of the rougher-bed. Fig. 8 represents a section on line $x'\ x'$, Fig. 4. Fig. 9 represents a section on line $x^2\ x^2$, Fig. 4. Fig. 10 represents a perspective view of the holder of the cutting-off tool.

The same letters of reference indicate the same parts in all the figures.

In the drawings, A represents the frame or bed of a lathe, having a longitudinal opening, the sides $a\ a$ of which constitute the guides or ways on which slide the tail-stock B and the carriage C.

Between the guides or ways a and the proximate surfaces of the carriage C and tail-stock B are interposed gibs or plates a^2 , which are backed by screws a^3 , passing through parts of the carriage and tail-stock, which are adjacent to the guides a . The gibs a^2 are rendered adjustable by means of the screws, so that they will take up or prevent any lost or lateral motion between the carriage and tail-stock and the guides $a\ a$, and thus enable said carriage

and tail-stock to be kept perfectly true without the slightest lateral displacement. The plates and screws enable the inevitable wear of the rubbing-surfaces of the guides and carriage and tail-stock to be compensated for with but slight cost.

D represents the inner end of the head-stock, the same being supported from the bed A by suitable means, (not shown in the drawings.)

To the carriage C are attached the center-rest E and the roughing-tool F. The roughing-tool is supported on a rougher-bed, B', which is composed of a base, 2, and an upper section, 3. The base 2 is connected at its inner end by a pivot, 4, to the center-rest, so as to be capable of swinging vertically, and is secured at its outer end by a screw, 5, passing through a slot, 6, in the center-rest, said slot and screw enabling the bed to be turned on the pivot 4 to vary the inclination of the roughing-tool.

The section 3, to which the roughing-tool is directly attached by a clamp, 7, is connected to the base 2 by a pivot, 8, so that the section and tool can be turned laterally on the base to vary the angle of presentation of the roughing-tool to the stick being turned, and therefore cause the tool to remove a chip which is more or less "rank." In other words, the cutting end of the roughing-tool can be fixed at any desired angle to the stick, the rankness or depth of the cut increasing with the angle formed by the cutting end of the tool and the stick, and vice versa.

The section 3 is provided with a rigid arm, 9, in which is journaled a bolt, 10, the inner end of which is threaded, and enters a threaded orifice in the base 2 of the rougher-bed. By turning the bolt 10, which is provided with fixed collars or enlargements on each side of the arm 9, so that it cannot move lengthwise independently of said arm, the upper section, 3, of the rougher-bed is turned on its pivot in one direction or the other, said section being positively held by the bolt 10 at any point to which it may be adjusted.

The clamp 7 of the roughing-tool is preferably secured by the screw which constitutes the pivot 8.

The carriage C is provided with lugs G G, to which is pivoted the shank H' of the tool-holder H, the pivot being a tapering pin, I,

the main portion of which rests in a similarly-tapered socket of the shank. The tapering form of the pin and its socket enables the pin, when moved lengthwise, to closely fill the socket and prevent lost motion of the tool-holder on the pin. I provide the ends of the pin with check-nuts J J to enable it to be adjusted lengthwise.

W represents an oil-cup or hollow boss formed on the shank H' and communicating with the socket of the pin I, so as to lubricate the latter. The tool-holder is enabled by its pivot to oscillate toward and from the work supported by the head and tail stocks, so as to cause the tool or tools held in the cavity H² of the tool-holder to approach and recede from the work.

The shank H' of the tool-holder is composed of two parts, as shown in Figs. 1 and 2—viz., the lower part, pivoted to the lugs G G, and provided with a recess or mortise, r, in its upper end, and the upper part, having the tool-holder H², and provided with a tongue or tenon, r', projecting downwardly into the mortise r and adapted to slide vertically therein, so as to adjust the tool-holder vertically.

The tool-holder is secured to the lower part of the shank in any position to which it may be adjusted by a bolt, r², having a clamping-nut and passing through the lower part of the shank H' and through a slot, s, in the tongue r'. Provision is thus made for regulating the height of the tools in the holder H² to suit the requirements of the work.

K represents the cutting-off tool, which is attached to a holder, L, which is adjustably secured to a slotted bracket, L', attached to a slide or plate, M, adapted to reciprocate vertically between guides N N on the inner side of a plate, C', which is adjustably secured to one of the side pieces of the carriage C. (See Fig. 4.)

The holder L has a vertical slot, l', in one side, over which project lips l² l², and in its opposite side is provided with horizontal slots l³, which are cut through to meet the slot l'. The slot l' receives the cutting-off tool, and the slots l³ receive the parts or arms of the bracket L' on either side of the horizontal slot of said bracket.

The holder L is provided with a threaded stud, l⁴, which projects through the slot of the bracket L', and has a nut, l⁵, which bears against the bracket L', and when screwed home binds the tool K, the holder L, and the bracket L' firmly together, the tool K bearing against the side of the bracket opposite to that on which the nut bears, and being drawn toward the bracket by the action of the nut, which bears at once on the two arms of the bracket, and thus secures the tool K at two points.

The horizontal slot in the bracket L' enables the holder L and tool K to be adjusted horizontally in a direction at right angles to the stick, so that the point of the tool K, as it rises, may be caused to move directly toward the center of the stick or toward a point out-

side of the center. The tool K is made laterally adjustable, so as to cut off the stick at any desired point by means of a horizontal slot, l⁶, in the side piece of the carriage C, (see Fig. 8,) a stud, l⁷, projecting from the back of the plate C' through said slot and a clamping-nut, l⁸, on the stud. The cutting-off tool is therefore enabled to be moved laterally or lengthwise of the stick a distance proportioned to the length of the slot l⁶, and is held by the nut l⁸ in any position to which it may be adjusted.

The lower end of the slide M is provided with a pin, M', which enters a slot, O, in an angular knee-lever, P, which is pivoted at R³ to an arm, S, rigidly attached to and projecting downwardly from the carriage C.

R' represents a spiral spring, one end of which bears upon one of the teeth or shoulders of a toothed disk, R², which is affixed to the outer end of the axle or stud R³, on which the knee-lever is pivoted, the spring R' being coiled upon the axle R³. The other end of the spring bears upon the pin M' of the slide M and exerts a downward pressure thereon, whereby the cutting-off tool, the knee-lever, and the connected parts hereinafter described are quickly restored to their normal positions when the knee lever is released.

The tension of the spring may be regulated by engaging it with different teeth or shoulders of the disk R², the end of the spring being bent to form a tooth adapted to engage with either of the teeth of the disk R².

U represents a vertical slide having at its lower end a pin, V, entering the slot O and extending upwardly between guides b b on a plate or lever, e, which is pivoted at d' to a portion of the carriage C. (See Fig. 3.) The slide U is adapted to reciprocate vertically between its guides b b, and is connected by a link, d, with the lower end of the shank H' of the tool-holder H.

It will be observed that when the outer end of the lever P is pressed inwardly by the knee of the operator in the direction indicated by the arrow in Fig. 2 its inner end will be raised and caused to raise both the slide U and the slide M in consequence of the engagement of the pins V and M' of said slides with the slot O of the lever. The pin M' of the slide M is in the inner end of the slot O, while the pin V of the slide U is in the outer end of said slot. Hence the slide U is raised more rapidly than the slide M. When the slide U is depressed the link d is inclined upwardly from the slide to the shank H' of the tool-holder, and when said slide is raised the link first approaches a horizontal position and then becomes inclined, in doing which it first turns the shank of the tool-holder on its pivot, so as to move the tool-holder inwardly toward the work and then in the opposite direction, so as to move the tool-holder away from the work. Meanwhile the cutting-off tool K is being raised by the slide M, but the inward movement of the tool-holder and the consequent action of the tool or tools held thereby is com-

pleted before the cutting-off tool commences to act on the work, said tool commencing and completing its action while the tool-holder is moving away from the work. The tool-holder 5 and cutting-off tool are therefore operated successively and by the same knee-lever, their operation being to a certain extent automatic—that is to say, the cutting-off tool cannot operate until the reducing tool or tools of the tool-holder C have done their work and the reducing tool or tools cannot interfere with the cutting-off tool.

The plate or lever c, having the guides b b of the slide U, may be turned on its pivot d' 15 by means of a screw-shaft, i, journaled in a lug, j, on the carriage C, said shaft passing through a threaded orifice in a lug, k, on the plate c. The object of turning the plate c on its pivot is to vary the inclination of the guides b b and slide U, and thus, through the medium of the link d, vary also the inclination of the pivoted stock H' of the tool-holder H, so that the latter may stand normally nearer to or farther from the work. The screw-shaft i is provided with a hand-wheel, m, for convenience 25 in rotating it.

To prevent lateral motion of the carriage C, I interpose between it and one of the guides a strip of sheet metal, n, preferably steel.

30 p represents a back-stop on the carriage C, to limit the outward movement of the tool-holder.

It will be observed that the slotted bracket L' and the holder L, slotted to receive the 35 bracket, and the laterally-adjustable plate C', guiding the slide to which the bracket is rigidly affixed, constitute a very firm substantial support for the cutting-off tool, permitting its adjustment both crosswise and lengthwise of 40 the stick. The adjusting and operating movements of the cutting-off tool are all rectilinear and controlled by guides, there being no pivots nor oscillating movements.

I am aware that a cutting-off tool having 45 right-angular intersecting grooves therein and a binding-screw for confining the tool and its holder is not new. I therefore confine myself to the construction claimed.

I claim—

50 1. In a lathe, the combination, with the center-carriage, of the roughing-tool holder, base 2, pivoted to the center-carriage, and made vertically adjustable at one end, as described, the upper section, 3, having means for holding 55 the roughing-tool, pivoted to swing laterally on the base 2, and provided with the arm 9,

and the screw-bolt 10, journaled in the said arm, and working in a tapped socket in the base 2, whereby the rougher-tool is adjusted laterally, and positively held at any position 60 to which it may be adjusted, as set forth.

2. The combination, with the work-holding devices, of the tool-holder having a pivoted stock, the cutting-off tool, adapted to be reciprocated in fixed guides, the pivoted slotted 65 lever P, the slide M, supporting the cutting-off tool, and engaged with the inner end of the slot of the lever P, and the slide U, engaged with the outer end of said slot, and connected with the stock of the tool-holder by a link, d, 70 the engagement of the slides M and U respectively with the outer and inner ends of said slot causing the slide U to be raised more rapidly than the slide M, as set forth.

3. The combination, with the tool-holder and 75 its pivoted shank, of the slide U, connected to the shank by the link d, the pivoted plate c, having the guides of the slide U, and means for turning the plate c on its pivot to effect the adjustment of the tool-holder through the intermediate devices, as set forth.

4. The combination of the tool-holder, its shank H', having a tapering socket, and the tapering pin I, lugs G G, and thumb-nuts J, substantially as described, whereby the lost 85 motion may be provided against, as set forth.

5. The combination, with the holder L, provided with fastening-screw, of the slotted clamp L', slide M, guides N, plate C', slotted center-carriage C, screw l', and nut l", substantially as described, whereby vertical, longitudinal, and side motion is given the tool-holder, as set forth.

6. The combination of the cutting-off tool K, the holder L, having a vertical slot, l', in one 95 side to receive said tool, and transverse slots l² l³ in the other side, meeting the slot l', the slotted bracket L', the arms or parts of which are fitted in the slots l², the screw-stud l⁴ and its nut, having the enlarged head adapted 100 to bear at once on the two arms of the bracket, and the tool K, whereby the holder L is secured or clamped at two points, as set forth.

In testimony whereof I have signed my name to this specification, in the presence of sub- 105 scribing witnesses, this 28th day of April, A. D. 1882.

CHARLES H. COWDREY.
